ABSTRACT OF THE DISCLOSURE

The bearing pin on which the armature of a relay is pivotally mounted to the relay heel piece is secured in apertures in upturned ears of the armature by deforming the soft armature material around and above the apertures sufficiently to cause the bearing pin and the apertures to assume an out of round shape.

BACKGROUND OF THE INVENTION

Field of the invention

This invention relates generally to relays and more particularly to a method of securing the armature bearing pin on relays or rotary switches.

Electromagnetic relays of the type having a bearing pin secured to the armature are extensively used in telephone systems and have proven quite satisfactory. During the many operations of a relay the armature is subjected to a pounding action when it strikes the relay core and this repeated operation may gradually loosen the bearing pin in the armature. As the bearing pin becomes loose the mechanical and electrical characteristics of the relay are altered to such an extent that the relay can no longer be adjusted to perform the function it was designed to accomplish.

Prior art

A variety of methods of securing the bearing pin to a relay armature, including the following, have heretofore been used:

(1) Knurl one end of bearing pin and force fit into armature hole and flare other end.

(2) Insert bearing pin having no knurling, but having coaxial holes drilled in both ends, into armature holes and flare both ends against outer armature surface.

(3) Insert pin having holes in both ends into armature and stake using round or square stake to expand armature bearing pin outward against magnetic iron material.

The above methods attempt to secure a stainless steel or Phosphor bronze bearing pin to the annealed magnetic iron armature by a flaring and/or staking operation which expands a hard resilient, memory retaining, high spring back characteristic type material against a relatively dead soft annealed magnetic iron material having a poor memory, or practically no spring back characteristic. Consequently, after the flaring or staking operation, the resilient bearing pin tends to spring back to its original shape. The soft armature material, on the other hand, takes a set to the maximum expansion caused by the flaring or staking operation. These two diametrically opposed actions of the mating parts allows a relaxation of the tightness between the surface engagement of the bearing pin and the armature material, resulting in loose armature bearing pins.

It is a general object of this invention to increase the reliability and to reduce the cost of maintenance of relays.

Another object of the invention is to provide an im-

2

proved technique for securing the bearing pin to a relay armature.

SUMMARY OF THE INVENTION

The present invention provides a means to secure the armature bearing pin to the armature to prevent the bearing pin from rotating. The bearing pin, with coaxial holes drilled in each end, is inserted into openings in the upstanding ears of the armature. Pressure applied to the periphery of the ears in a direction normal to the axis of the bearing pin, sufficient to distort the roundness of the hole in the armature ear and the end of the bearing pin, prevents the bearing pin from rotating.

DESCRIPTION OF THE DRAWING

The nature of the invention and its distinguishing features and advantages will be more clearly understood from the following detailed description, taken in conjunction with the accompanying drawing, wherein:

FIG. 1 is a top or plan view of a relay;
 FIG. 2 is a side view of the relay shown in FIG. 1;
 FIG. 3 is a perspective view of the armature assembly;
 FIG. 4 is an enlarged side view of an ear of the armature showing the deformed end of the armature bearing pin; and
 FIG. 5 is a cross-sectional view taken along the line 5—5 of FIG. 4.

DETAILED DESCRIPTION

Referring now to the drawings, and more particularly to FIGS. 1 and 2, there is shown an electromagnetic relay 10 having the usual field structure comprising a core 25, a winding and an L-shaped heel piece 23 secured to the core by means of a screw 24. An armature 12 is pivotally secured to the heel piece by a bearing pin 16, a yoke 13, a clamp washer 14 and a screw 15. The yoke has bearing points at 21 and 22 for the bearing pin 16.

As better seen in the perspective view of FIG. 3, the bearing pin 16 is rigidly secured in holes or openings in the upturned ears 17 and 18 of the armature 12. The bearing pin 16 has a hole 20 drilled in each end thereof to a depth of approximately the thickness of the ear. As in conventional relays, armature 12 is formed of soft magnetic iron, which has a low elastic limit. The bearing pin 16, on the other hand, is formed of a hard material, such as Phosphor bronze, which has a much higher elastic limit.

In accordance with the invention, the pin 16 is secured to the armature by deforming the material of the ears 17 and 18 from the shape indicated by the dotted lines in FIGS. 4 and 5 to the shape shown by the solid lines 19. This may be accomplished by clamping the armature assembly in a suitable jig and applying sufficient pressure to the ears at a point generally above the pin to collapse the material of the ears in the region above and around the pin, and the pin itself. The presence of the coaxial holes 20 in the ends of the pin 16 eases the deformation of the pin into a shape other than round—generally oval, as shown.

Unlike the prior art systems in which the differing elastic properties of the armature and pin compete in a way tending to loosen the pin, in the instant case the soft magnetic iron set in its deformed condition and the relatively more elastic Phosphor bronze pin, which tends to restore to its original shape, maintains rigid contact with the material of the upstanding ears. That is, the different elastic properties cooperate to maintain secure contact between the pin and armature. The out-of-round shape of the pin, and the continuously applied force against the surfaces of the deformed apertures, prevent loosening of the pin and rotation of the pin relative to the armature.

While the invention has been described as applied to a relay, it will be recognized that it has utility in any situation where it is desired to secure a pin of high elasticity to a member of relatively lower elasticity.

What is claimed is:

1. In a switching device; an armature of a magnetic material having a substantially low elasticity; an ear formed on said armature; a bearing pin of a material having a substantially high elasticity; an opening in said ear and having one end of said bearing pin inserted therein; a coaxial opening in said one end of said bearing pin, and extending therein to a depth approximating the thickness of said ear; said coaxial opening enabling the simultaneously deforming of said opening in said ear, said one end of said bearing pin and said coaxial opening, in response to the deforming of a portion of the periphery of said ear in a direction normal to the axis of said bearing pin, for permanently engaging said one end of said bearing pin with said ear; said one end of said bearing pin thereafter maintained in said permanent engagement with said ear in response to the differences in said elasticity of said armature and said bearing pin materials.

2. In a switching device; an armature of a magnetic material having a substantially low elasticity; an ear formed on each side edge of said armature, and extending at right angles to the plane of said armature; a bearing pin of a material having a substantially high elasticity; an

opening in each said ear; each said ear opening engaged by an end of said bearing pin; a coaxial opening formed in each end of said bearing pin, and extending therein to a depth approximating the thickness of each said associated ear; said coaxial openings enabling the simultaneous deforming of said openings in said ears, said ends of said bearing pin and the coaxial openings, in response to the deforming of a portion of the periphery of each said ear in a direction normal to the axis of said bearing pin, for permanently engaging each said end of said bearing pin with the associated said ear; each said bearing pin end thereafter maintained in said permanent engagement with said associated ear in response to the differences in said elasticity of said armature and said bearing pin materials.
